CLAIM

The ornamental design for a shoe, as shown and described.

DESCRIPTION

1. Shoe
